INVENTOR.

Henry C. Hill
BY
John W. Trebil ATTORNEY.

UNITED STATES PATENT OFFICE.

HENRY C. HILL, OF CINCINNATI, OHIO.

AUTOMOBILE SPEED CONTROLLER.

Application filed January 24, 1923, Serial No. 614,669. Renewed January 9, 1925.

To all whom it may concern:

Be it known that I, HENRY C. HILL, a citizen of the United States, residing at the city of Cincinnati, in the county of Hamilton and State of Ohio, have invented certain new and useful Improvements in Automobile Speed Controllers, of which the following is a specification.

My invention relates to that class of speed controllers for automobiles which operate by automatically grounding the primary circuit of the ignition system to the spark plugs, when the predetermined speed of automobile has been reached, and more particularly to the switch or electrical terminal of such controllers.

The speed controller as a mechanism is fully described in U. S. Letters Patent issued to me December 13, 1921, Number 1,400,062 and in a pending application for patent serial Number 527,515, and need not be further described herein, excepting that it consists essentially of a centrifugal spring governor of a suitable type taking motion from the running gear of the automobile.

In the accompanying drawing Fig. 1, shows a centrifugal spring governor, or controller containing my improved terminal. Fig. 2 is a plan view Fig. 1. Similar letters of reference indicate similar parts.

A, is the body or frame of a centrifugal spring controller to which my present improvement is applicable. B, the revolving mechanism consisting of a square shape B¹ driven by a horizontal shaft and miter gears in the usual manner. At the lower end of the shape B¹ is rigidly attached a hub or collar b⁵, carrying pivoted weighted arms b¹ which expand and contract according to the speed of the shaft. Links b⁸, connect the weighted arms to a revolving sliding collar b⁴, at the upper end of shaft B¹. The collar revolves with and slides down and up on the square shaft as the speed of the shaft is increased or decreased. The centrifugal force of the controller is furnished by the revolving pivoted weighted arms b¹, and the centripetal or reacting force is furnished by the spiral b⁷, which reacts between the fixed hub b⁶, and the sliding sleeve b⁴.

Attached to the upper end of the collar b⁴, and integral therewith, is a disc C, which revolves and moves down and up with the sleeve, and when the automobile and correspondingly the controller has attained the

limiting travel speed, the underside of the disc C impinges upon a friction roller d, mounted upon a lever or terminal member D pressing this member downwards until the points d³, make electrical contact and grounds the primary circuit of the ignition system, and suppresses the spark in the engine cylinder.

The terminal member is pivoted to the frame at d², and is provided with a reaction spring d⁴, and an adjustable stop d⁵, to limit the upward travel or reaction of the lever D.

Mounted in the bracket d¹ at the right side of frame A, is an insulated plunger d⁶, provided at the upper end with an electrical terminal point d⁸, and at the lower end with a lock nut adjustment d⁹, and a spiral reaction spring d⁷. d⁶ is a shell of insulating material as fiber, vulcanized rubber or any suitable material in which the plunger d⁶, and spring d⁷, are mounted. The lock nuts also secure the clip or eye of the conductor E, the other end of which is attached to a convenient ground of the primary circuit.

The plunger d⁶, is made yielding to pressure from the lever D, and contact points d³, by spring d⁷, in order that the controller may not be injured or the predetermined speed limit be altered by continued contact of the points d³, or pressure from the lever D, when the automobile from any cause is running at a higher speed than the predetermined speed for which the controller is adjusted.

The speed and speed limit is rated in miles per hour, and the revolutions of the travel wheels per mile will vary with their diameters, being more for wheels of small diameter than for wheels of large diameter; consequently the revolutions of the controller will vary with the diameters of wheels, and adjustment must be provided to produce a given travel speed limit of the automobile for all wheel diameters.

This is accomplished by the adjustable stops d², and d⁵, and plunger d⁶. By raising the stop d² the proper amount and lowering the jam nuts d⁹, and raising the plunger d⁶, by reaction spring d⁷, correspondingly, the speed limit will be adapted to the wheels of larger diameter, and by reverse action to wheels of smaller diameter. The sliding movement of the disc C, on the shaft B¹, will accordingly be less for larger travel

wheels than it will be for smaller travel wheels. The controller is nominally adjusted to a wheel 33 inches diameter.

- The action of the device is obvious from an inspection of Fig. 1. The terminal member D, is pressed downwards by the revolving sliding disc C, and upwards by the reaction spring d¹, and oscillates between the stop d², and the upper end of the plunger d⁴.
- 5 When the electrical points d³, impinge by the downward movement of the terminal member, the primary ignition circuit is grounded, and the spark in the engine cylinders momentarily suppressed.
- 10 A slight reduction of speed causes the governor balls to contract the disc C, and lever D, to rise, and the electrical points d³, to separate, whereupon the ignition system is restored until such time as the speed limit 15 is again reached and the described action of the parts C, D, and d³, is repeated.
- In former terminals for automatic speed controller for automobiles, where the electrical contact is made between a revolving sliding disc on the controller shaft, and an insulated electrical grounding member, the spark caused by "making" and "breaking" contact of the disc and grounding member has fused and roughened the contact surfaces, increasing the wear and changing the predetermined speed limit to which the controller was adjusted. To overcome this objection the electrical contact points are made of a refractory alloy having some of the 20 properties of platinum and placed as shown at d³, one at the free end of the lever D, and

the other at the upper end of the plunger d⁴, so that as the point in the end of the lever impinges and recedes from the point in the plunger, electrical contact is made and broken, and sparking at the points will not injure them or change the adjusted speed limit of the controller.

Claim.

40 A speed controller for automobiles comprising a frame, a centrifugal spring governor mounted and revolving in said frame, an oscillating lever pivoted at one end to said frame and provided at the free end with an electrical contact point, means controlled by the travel speed of the vehicle to depress said lever, means to raise said lever when the depressing means is retracted, means adjustable to limit the reaction of 45 said oscillating lever, a resilient electrical contact member which is impinged and depressed by the contact point in the free end of said oscillating lever when the speed limit has been reached, said impinged contact member mounted in an insulating shell 50 and provided with a reciprocating plunger and reaction spring, means adjustable to limit the upward movement of said impinged contact member, and a conductor to connect said impinged member to a ground, 55 whereby the current to the spark plugs is suppressed.

60 In testimony whereof, I affix my signature at Cincinnati, Ohio, this 22nd day of January, 1923.

HENRY C. HILL.
